UNITED STATES PATENT OFFICE.

EDWIN AUGUSTUS BROOKER, OF LONDON, ENGLAND.

TOBACCO PIPE.

Application filed December 10, 1925, Serial No. 74,513, and in Great Britain December 16, 1924.

This invention relates to tobacco pipes and it has for its object certain improvements designed not only to secure the dry smoking of the said pipe but to enable the pipe to be readily cleaned when so desired.

According to this invention the pipe is provided within the bore of the stem and mouthpiece with a hollow body longitudinally divided either constructionally or by means fitted therein, or provided with longitudinally extending parts, in each case for the purpose of retaining a compact removable absorbent body in a part only of the bore of the stem and mouthpiece, so that the pipe has a clear smoke passage from the bowl to the mouthpiece end.

In order that the invention may be the better understood drawings are appended in which:—

20 Fig. 1 is a longitudinal section of a pipe embodying the present invention,

Fig. 2 is a perspective view of the body carrying the absorbent material removed from the pipe,

25 Fig. 3 is a longitudinal section of a pipe embodying an alternative form of the invention,

Fig. 4 is a perspective view of the body shown in Fig. 3, for carrying the absorbent material,

30 Fig. 5 is a perspective view showing a further modification.

Referring to Figs. 1 and 2 of the accompanying drawings, *a* indicates the body of the pipe and *b* the mouthpiece.

35 Disposed within the bore of the stem of the pipe, which is of such diameter as to snugly contain it, is a tubular body *c* divided longitudinally by a perforated strip or plate of metal *d*. The width of the strip at one end is increased as shown at *d*¹, *d*², to form projections which engage slits formed in the end of the said body, and so serve to hold the strip against displacement.

40 The bore of the mouthpiece is also enlarged for a certain portion of its length to receive the body *c*.

45 *e* indicates the absorbent body which may conveniently comprise a pipe cleaner of the kind formed by a twisted wire engaging woollen or other fibres. The cleaner, when doubled upon itself, is inserted beneath the perforated strip *d* and may be readily withdrawn and a fresh one substituted.

50 The end of the body *c*, where it enters

the bowl of the pipe, is cut away as shown thereby permitting the ready entry of the smoke to the body *c*.

f indicates a projection upon the upper portion of the circumference of body *c*, said projection engaging a slit or recess *c*¹ formed at the outer end of the flock *x*, and by means of which not only is the proper positioning of the said body *c* ensured, but its rotation independently of the mouthpiece is prevented.

In the alternative arrangement illustrated in Figs. 3 and 4 the body *c* is of substantially semi-circular cross-sectional outline and is provided upon each side with internal projections *g* running longitudinally thereof, a sufficient space being left between said projections for the moisture to pass to the absorbent body, *e*.

55 In order to prevent lateral or vertical movement of the body within the bore of the stem and mouthpiece there are provided at certain points in the length of said body archshaped portions indicated by *h* so that at these points the body is of circular cross-sectional outline and fits snugly within the bore of the stem and mouthpiece.

60 In the modification shown in Fig. 5, the absorbent carrying body is constructed to provide two tubular members, disposed side by side and of such diameter as to each contain one half of a pipe cleaner folded or doubled as previously explained. Openings are provided at the side of the members, as indicated at *h*¹, through which moisture 65 may pass to the said body.

65 As the fibres of the cleaner project slightly through the openings *h*¹ and contact with the surface of the bore of the stem and mouthpiece, by rotating said body it will 70 act to remove any matter thereon and so keep the pipe clean.

75 By means of the present invention any moisture resulting from condensation in the stem or mouthpiece is absorbed by the body 80 *e* and its entry to the bowl of the pipe or the mouth is prevented.

85 Moreover, as the body *c* is removable and replaceable, it may be cleaned from time to time as may be necessary and the absorbent 90 body readily renewed.

Claims:

1. A tobacco pipe, embodying a bowl, a stem associated with said bowl and provided with a smoke passage, a mouthpiece asso. 110

- ciated with the stem, a smoke passage in said mouthpiece, a hollow body in the smoke passage in said stem, an enlargement in the bore of the smoke passage in said mouthpiece, into which enlargement said hollow body extends, and means disposed longitudinally of and upon each side of said body to removably retain an absorbent body in part only of the bore of the stem and mouthpiece so that the pipe has a clear smoke passage above said absorbent body from the bowl to the mouthpiece end, said absorbent body extending from end to end of said hollow body, said hollow body having openings therein exposing the absorbent material.
2. A tobacco pipe, embodying a bowl, a stem associated with said bowl and provided with a smoke passage, a mouthpiece associated with the stem, a smoke passage in said mouthpiece, a hollow body in the smoke passage in said stem, an enlargement in the bore of the smoke passage in said mouthpiece, into which enlargement said hollow body extends and an absorbent body removably retained in said hollow body in part only of the bore of the stem and mouthpiece so that the pipe has a clear smoke passage above said absorbent body from the bowl to the mouthpiece end, said absorbent body extending from end to end of said hollow body; said hollow body comprising a tube having longitudinal openings therein exposing the absorbent body, and inturned lugs upon said openings to engage said absorbent body;
3. A tobacco pipe, embodying a bowl, a stem associated with said bowl and provided with a smoke passage, a mouthpiece associated with the stem, a smoke passage in said mouthpiece, a hollow body in the smoke passage in said stem, an enlargement in the bore of the smoke passage in said mouthpiece, into which enlargement said hollow body extends, means disposed longitudinally of said body to removably retain an absorbent body in part only of the bore of the stem and mouthpiece so that the pipe has a clear smoke passage above said absorbent body from the bowl to the mouthpiece end, said absorbent body extending from end to end of said hollow body, said hollow body comprising a tube having longitudinal openings therein exposing the absorbent body, and inturned lugs upon said openings to engage said absorbent body; said absorbent body extending from end to end of said hollow body comprising a tube having longitudinal openings therein exposing the absorbent body, and inturned lugs upon said openings to engage said absorbent body; a projection upon said tube and a slit in the flock of the mouthpiece to engage said projection.
4. A tobacco pipe, embodying a bowl, a stem associated with said bowl and provided with a smoke passage, a mouthpiece associated with the stem, a smoke passage in said mouthpiece, a hollow body in the smoke passage in said stem, an enlargement in the bore of the smoke passage in said mouthpiece, into which enlargement said hollow body extends, an absorbent body movably retained in said hollow body in part only of the bore of the stem and mouthpiece so that the pipe has a clear smoke passage above said absorbent body from the bowl to the mouthpiece end, said absorbent body extending from end to end of said hollow body; said hollow body comprising a tube having opposed longitudinally disposed inturned edges.
5. A tobacco pipe, embodying a bowl, a stem associated with said bowl and provided with a smoke passage, a mouthpiece associated with the stem, a smoke passage in said mouthpiece, a hollow body in the smoke passage in said stem, an enlargement in the bore of the smoke passage in said mouthpiece, into which enlargement said hollow body extends, an absorbent body removably retained in said body in part only of the bore of the stem and mouthpiece so that the pipe has a clear smoke passage above said absorbent body from the bowl to the mouthpiece end, said absorbent body extending from end to end of said hollow body; said hollow body comprising a tube having opposed inturned edges; a projection upon said tube, and a slit in the flock of the mouthpiece engaging said projection.

In testimony whereof I have hereunto set my hand.

EDWIN AUGUSTUS BROOKER.
